UNITED STATES PATENT OFFICE

140,938

DESIGN FOR A CANDLESTICK

Nancy L. Wade, Los Angeles, Calif.

Application May 22, 1944, Serial No. 113,714

Term of patent 14 years

(Cl. D48—2)

To all whom it may concern:

Be it known that I, Nancy L. Wade, a citizen of the United States, residing at Los Angeles, in the county of Los Angeles and State of California, have invented a new, original, and ornamental Design for a Candlestick, of which the following is a specification, reference being had to the accompanying drawing, forming part thereof.

The hatched areas denote portions whose color contrasts with the plain portions of the article.

I claim:

The ornamental design for a candlestick, as shown and described.

NANCY L. WADE.
